FOREIGN PATENT DOCUMENTS

WO 2006/054168 A1 5/2006

* cited by examiner

Primary Examiner — Terry Wallace(74) *Attorney, Agent, or Firm* — Lowe Graham Jones PLLC(57) **CLAIM**

I claim the ornamental design for the colander, as shown and described.

DESCRIPTION

FIG. 1 is a top perspective view of the colander, showing my new design.

FIG. 2 is a front view of the colander, the rear view being identical.

FIG. 3 is a right side view of the colander, the left side view being identical.

FIG. 4 is a top view of the colander; and,

FIG. 5 is a bottom view of the colander.

Features illustrated in broken lines form no part of the claimed design.
